UNITED STATES PATENT OFFICE

91,283

DESIGN FOR A COMBINED WRINGER AND CASING FOR WASHING MACHINES

Clement D. Ryan, Chicago, Ill., assignor to Montgomery Ward & Co., Incorporated, Chicago, Ill., a corporation of Illinois

Application October 9, 1933. Serial No. 49,425

Term of patent 7 years

To all whom it may concern:

Be it known that I, CLEMENT D. RYAN, a citizen of the United States, residing at Chicago, in the county of Cook and State of Illinois, have invented a new, original, and ornamental Design for a Combined Wringer and Casing for Washing Machines, of which the following is a specification; reference being had to the accompanying drawing, forming a part hereof.

In the drawing,

Fig. 1 is a side elevation of a combined wring-

er and casing for a washing machine showing my new design;

Fig. 2 is a similar view with the machine positioned at right angles to the position illustrated in Fig. 1; and

Fig. 3 is a top plan view of the machine.

I claim:

The ornamental design for a combined wringer and casing for washing machines, as shown.

CLEMENT D. RYAN.
